United States Patent Office

Des. 195,748
Patented July 23, 1963

195,748

PUMP

Ernest T. Lorenz, Bellmore, Long Island, N.Y., assignor to
Red Jacket Manufacturing Co., Davenport, Iowa, a
corporation of Iowa

Filed Nov. 28, 1961, Ser. No. 67,732

Term of patent 7 years

(Cl. D65—1)

FIGURE 1 is a perspective view of a pump embodying my new design;

FIG. 2 is a top plan view thereof;

FIG. 3 is a side elevational view thereof, the opposite side being a mirror image of FIG. 3;

FIG. 4 is an elevational view of one end thereof, and

FIG. 5 is an elevational view of the end thereof opposite that shown in FIG. 4.

The portions shown in broken lines is for illustrative purposes only.

I claim:

The ornamental design for a pump, substantially as shown and described.
